Cooper & Dunham LLP

(57) **CLAIM**

The ornamental design for a handle for a stamp, as shown and described.

DESCRIPTION

FIG. 1 is a perspective view of a handle for a stamp showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a referential perspective view of the handle thereof with a stamp shown in broken lines; and,

FIG. 9 is a referential perspective view of the handle thereof with another stamp shown in broken lines.

The portions of the Figures shown in broken lines are shown for illustrative purposes only and form no part of the claimed design.
